UNITED STATES PATENT OFFICE.

WILLIAM H. C. HIGGINS, JR., OF LAPORTE, INDIANA, ASSIGNEE TO M. RUMELY
COMPANY, OF LAPORTE, INDIANA, A CORPORATION OF INDIANA.

CARBURETER.

1,145,990.

Specification of Letters Patent. Patented July 13, 1915.

Application filed January 12, 1912. Serial No. 670,942.

To all whom it may concern:

Be it known that I, WILLIAM H. C. HIGGINS, Jr., a citizen of the United States, residing at Laporte, in the county of Laporte 5 and State of Indiana, have invented a certain new and useful Improvement in Carbureters, of which the following is a specification.

My invention relates to improvements in carbureters, and one application of it is illustrated in the accompanying drawings, wherein—

Figure 1 is a section through the carbureter; Fig. 2, a section along the line 2—2 15 of Fig. 1.

Like parts are indicated by the same letter in all the figures.

The shell A having the ends A¹, A², and top A³ makes with the wall A⁴ the carbureting or mixing chamber A⁵.

B is a hydrocarbon or fuel nozzle controlled by the valve B¹. C is a similar water or liquid nozzle, both of them discharging into the carbureting or mixing chamber A⁵.

25 D is a mixture discharge port in the end A¹ of the casing and D¹, the connection which leads thence to the engine.

E in the end A² of the casing is an air intake port in communication with the air intake passage E¹.

30 The gate valves F, F¹ which control the ports D and E are slidably mounted upon the opposed end walls A¹, A², and are controlled by the rods F², F³, projecting through 35 the top A³. The screw-threaded lever F⁴ is provided at either end with the slots F⁵ to engage the pins F⁶ on the slide rods F², F³, and is mounted upon the collar F⁷ which is 40 adjustably held by the nuts F⁸ and which is pivotally mounted upon the lug F⁹, which is adjustably held upon the top A³ by the screw F¹⁰ in the slot F¹¹. The valves may be operated in any suitable manner from any suitable source by the connecting rod G which 45 is pivotally mounted upon the collar G¹ which, in turn, is adjustably mounted upon the rod F⁴ and held in position by the nuts G².

It will be evident that while I have shown 50 in my drawings an operative device, still many changes might be made in the size, shape and arrangement of parts without departing materially from the spirit of my invention and I wish, therefore, that my drawings be regarded as in a sense diagrammatic.

It will be understood, of course, that my invention is applicable to the use of any kind of hydro-carbon fuel such as oil, gasoline, alcohol and other similar fluids.

60 The use and operation of my device are as follows:—I provide a carbureting or mixing chamber with an air inlet and a mixture discharge communicating with the engine. The engine draws its charge through the carbureting or mixing chamber and a vacuum is created within such chamber which 65 vacuum operates to draw the hydrocarbon and water to form a combustible mixture from the needle valve or other liquid supply. The amount of gas or air passing out 70 of the carbureter is varied to control the speed of the engine and when this amount of air is varied it will be obvious that the 75 vacuum in the carbureting or mixing chamber must also be varied in order to produce a combustible mixture. This variation I produce by giving the valves controlling the air intake and mixture discharge ports, a relatively variable motion and this is done by mounting the gate valves upon either end 80 of the rocking lever, the position of the fulcrum of which may be adjusted, thus giving a different relative movement to each of the two valves for the same angular displacement of the lever. The connecting rod which 85 actuates the lever is adjustably mounted thereon and by an empirical adjustment of the position of the fulcrum and the position of the connecting rod it will be evident that some point may be found at which the controlling motion of the connecting rod will 90 give a satisfactory combustible mixture for any position of the valves, and perfect combustion will then be found by starting at full load with the air intake and mixture 95 discharge ports in the open position. The fulcrum of the lever F⁴ will be so placed that for any movement of the connecting rod G the movement of the valve F¹ will be less than that of the rod F. The engine will 100 then be slowed down until a point is reached at which the mixture will be no longer satisfactory either because of too little or too much hydrocarbon; if because of too much hydrocarbon this will indicate too high a vacuum, and the fulcrum will be moved toward the right, giving a lesser movement of the valve F¹; if however because of too little hydrocarbon this will indicate too little 105 a vacuum, and the fulcrum will be moved 110

toward the left, giving a greater movement of the valve F^1 , the result being a greater vacuum. This adjustment will be continued until a point is reached at which combustion is perfect for all loads.

I claim:

1. In a carbureter, a vacuum chamber consisting of an extended body having fuel and water inlets each having a nozzle opening 10 into the carbureter chamber separate and distinct one from the other and adapted to vary but unequally their feeds responsive to variations in the vacuum in the carbureter chamber, an air inlet port at one end of the chamber and a mixture outlet port at the other end of the chamber in combination with flat slide valves adapted to travel transversely to the length of the chamber and control the ports, and means for simultaneously but unequally operating both of said valves during the operation of the engine, the water inlet adapted to feed only after the vacuum has substantially varied from its condition of no load and after the oil has been feeding and then to increase its feed disproportionately.

2. In a carbureter, a vacuum chamber consisting of an extended body having fuel and water inlets each having a nozzle opening 30 into the carbureter chamber separate and distinct one from the other and adapted to vary but unequally their feeds responsive to variations in the vacuum in the carbureter chamber, an air inlet port at one end of the chamber and a mixture outlet port at the other end of the chamber, in combination with flat slide valves adapted to travel transversely to the length of the chamber and control the ports, and means for simultaneously but unequally operating both of said valves during the operation of the engine, and adjustable connections between the two valves whereby their relations can be varied at will, the water inlet adapted to feed only 40 after the vacuum has substantially varied from its condition of no load and after the oil has been feeding and then to increase its feed disproportionately.

3. In a carbureter, a vacuum chamber consisting of an extended body having fuel and water inlets each having a nozzle opening 50 into the carbureter chamber separate and distinct one from the other and adapted to vary their feeds responsive to variations in the vacuum in the carbureter chamber, an air inlet port at one end of the chamber and a mixture outlet port at the other end of the chamber in combination with flat slide valves adapted to travel transversely to the 55 length of the chamber and control the ports, and means for simultaneously but unequally

operating both of said valves during the operation of the engine, the water inlet adapted to feed only after the vacuum has substantially varied from its condition of no 65 load and after the oil has been feeding and then to increase its feed disproportionately.

4. In a carbureter, a vacuum chamber consisting of an extended body having fuel and water inlets each having a nozzle opening 70 into the carbureter chamber separate and distinct one from the other and adapted to vary their feeds responsive to variations in the vacuum in the carbureter chamber, an air inlet port at one end of the chamber and 75 a mixture outlet port at the other end of the chamber, in combination with flat slide valves adapted to travel transversely to the length of the chamber and control the ports, and means for simultaneously but unequally 80 operating both of said valves during the operation of the engine, and adjustable connections between the two valves whereby their relations can be varied at will, the water inlet adapted to feed only after the 85 vacuum has substantially varied from its condition of no load and after the oil has been feeding and then to increase its feed disproportionately.

5. In a carbureter, a vacuum carbureter 90 chamber having fuel and water inlets each having a nozzle opening into the carbureter chamber separate and distinct one from the other and adapted to vary their feeds responsive to variations in the vacuum in the carbureter chamber, the water inlet adapted to feed only after the vacuum has substantially varied from its condition of no load and after the oil has been feeding, and an air inlet and a mixture outlet in combination with means for simultaneously but unequally varying both of their effective areas during operation, said means comprising separate valves controlling the air inlet and mixture outlet and means for moving 100 said valve simultaneously and means for varying the relative movement of the valves.

6. A carbureter having an air intake and mixture discharge passages and separate valves controlling them together with means 110 comprising a lever fulcrumed intermediate its two ends connected at one end to each of said valves and means for rocking said lever, said rocking means and said fulcrum being adjustable along the lever to vary the 115 relative movement of the valves and vary the response of the lever to the rocking means.
